SELECTIVE VENDING MACHINE.

Application filed August 5, 1925. Serial No. 48,274.

The present invention relates to selective vending machines and pertains more particularly to the fully selective type of machine invented by the undersigned and set forth in our co-pending application Serial Number 22,408.

Our present invention has among its objects the provision of a machine in which the articles are more easily selected and in which the contents of the machine may be learned without the necessity of operating the parts. Incidentally it is another object of the invention to increase sales by attractively displaying the wares to be vended by the machine.

Another object of the invention is to provide a selective vending machine adapted to handle and vend a wide variety of shapes, sizes and brands of articles, including articles varying in size and nature from sandwiches and individual pies to irregular shaped candy bars and the like. Given quantities of loose articles are even contemplated for vending, together with articles of standard shapes and sizes.

Another object of the invention is to hold all articles against movement and vibration, so that as the article holders are moved in the act of selecting an article, the contents of the machine are not moved in their respective holders.

Another and important object of the invention is to provide for efficiently holding, as well as properly ejecting, varied sizes of articles without subjecting the article to be vended to impact from a manually controlled or automatic ejector.

Another object of the invention is to thoroughly enclose and protect the articles to be vended against insects and the infiltration of dust and the like, and against damage by objects sometimes employed in attempts to rob the machine.

Another object of the invention is to provide improved article holding and ejecting means suitable to a wide variety of vending machines, both selective and otherwise.

Our invention contemplates the use of individual compartments or holders for containing the article or articles to be vended in

exchange for a coin. It is further contemplated to insert and remove the articles thru a closure which is adapted to be moved to closed position to retain and protect the contents. It is therefore among the objects of the invention to provide a machine embodying a large number of such compartments without the necessity of employing more than one coin controlled mechanism for effecting discharge of the contents of any selected holder.

It will be understood, in the consideration of the invention, that it is very expensive and impractical to employ a plurality of coin controlled mechanisms in one machine. In fact, in order to provide against operation by slugs and other trick devices, the requisite coin controlled mechanism is expensive enough. It is therefore an object of the invention to provide for controlling a large number of individual article holders with one coin controlled device, while providing separate closure for each and every article holder; all without undue cost.

Another object of the invention is to provide a machine which is easily replenished, attractive, sanitary, and which will provide more protection to both operator and the patron against mistakes and loss of money.

Another object of the invention is to provide means whereby gravity need not be depended upon to bring the purchased article into the hands of the patron, particularly where the object is of such character as to tend to lodge in the discharge chute.

Still other objects and advantages of our invention will appear hereinafter and will be better understood because of the order in which they appear.

We have illustrated our invention by the accompanying drawings in which we have shown one practical embodiment of our invention, also a slight modification thereof; it being understood that the embodiment and modification shown are merely typical of our invention, and are by no means representative of the wide variety of applications to which the various features of our invention are adapted. The drawings, together with the ensuing description, will enable those

skilled in the art to make and use the embodiments illustrated and described, and to further apply the various features to other vending machines and to conceive and construct numerous other embodiments employing our invention.

In the said drawings;

Figure 1 is a face view of the said embodiment of our invention.

10 Figure 2 is a side elevation thereof.

Figure 3 view in side elevation and section of one of the article holders employed; the view showing an article emerging therefrom.

15 Figure 4 is a section on the line 4—4 of Fig. 3.

Figure 5 is a vertical mid section, on a larger scale, of the machine shown in Figs. 1 and 2.

20 Figure 6 is a view in elevation and section seen principally on the line 6—6 of Fig. 5.

Figure 7 is a view in section seen on a line 7—7 of Fig. 5.

25 Figure 8 is a view in section seen on a line 8—8 of Fig. 7.

Figure 9 is a front elevation of a modified form of the machine shown in Fig. 1.

30 In carrying out the invention in the embodiment shown we provide front and rear casing walls, 15 and 16 respectively, connected by a peripheral wall 17, to provide a substantially inaccessible interior space 18. The casing is provided forwardly with a co-

35 axial opening 15^a covered by a window 15^b, so that certain hereinafter described parts are visible from points exterior to the casing.

40 Within the space 18 there is provided a plurality of article holders 19, adapted to contain any suitable article or articles such as a boxed sandwich 20, an irregular shaped candy bar 20', or two or more small objects such as 21, loose articles in large quantities may also be held in the article holder shown.

45 Each article holder is provided with a hinged closure generally indicated by the numeral 22. In the embodiment shown said closure is divided into two parts, 22^a and 22^b respectively. Each is hinged to a corresponding side wall 23, of the holder, by a hinge such as 24. Means, to be described hereinafter, are provided for holding the closure locked in closed position, and other means are provided for effecting the opening of a closure only as a result of introducing a coin to the machine.

50 The casing is provided with a discharge opening 25, provided in the peripheral wall, and it is among the purposes of the machine, and mechanism about to be described, for causing the contents of any selected one of the article holders, to pass into and thru the discharge opening, upon introduction of a coin and proper operation of coin controlled parts.

In the embodiment illustrated, the discharge opening and the chute 26, which leads outwardly therefrom, is fixed, while the article holders are collectively movable; the purpose being to bring any selected one 70 of the article holders into discharging registration with the chute, and to there effect opening of the closure to release the contents.

The article holder shown in Figs. 2 and 3 75 particularly, includes end walls 27 and 28 respectively, and a bottom wall 29. Thru the bottom wall extends a guide stem 30, which carries on its inner end a movable wall 31, arranged to travel in the interior 80 of the holder. Between the bottom wall and the movable wall a spring 31^a is inserted which tends to impel the movable wall outwardly.

Obviously each spring will act to hold the 85 corresponding movable wall against the contained article and said article in turn is held against the closure; thus the article is held from movement and vibration, and the closure fits closely enough to enclose the article 90 against foreign matter and to protect it from any objects that might be employed to damage or rob the machine. It will also be seen that when the closure is opened the spring will act to force the contents outwardly 95 without striking a blow. Rapid but careful and positive delivery of the contents of a holder is thereby assured.

The closure members are connected by 100 links 32, to a retractile bolt 33, which is slideable along one of the end walls of the holder. Said bolt has a right angle bend providing an extension 34. A bridge or yoke 35 passes over the bolt to guide same in its movements. A spring is connected at one end to the yoke 105 and at the other end to the extension 34 of the bolt. The tendency of the spring is to draw the extension toward the yoke so that the lower part of the bolt will move outwardly to carry the links and closures into 110 open position, as shown in Fig. 3 particularly.

To hold the closure members in closed position, against the urge of springs 36, there 115 is provided a latch 37. Said latch is riveted to the holder as at 38 while the remaining portions are free to be bent outwardly away from the holder. The metal employed in making the latch should have spring characteristics. The latch includes an outwardly 120 directed oblique portion or surface 39. Said latch also includes a step 40 adapted to engage the extension 34 on the bolt, when said bolt is in fully retracted, closed position. The spring characteristic of the latch holds the step in locking engagement with the extension 34 of the bolt, and thus the latch 125 will hold the closures indefinitely against the urge of any contained article. Obviously, a member such as 41, engaging the 130

surface 39 and moving parallel with the adjacent vertical wall of the holder, will act on the oblique surface of an operatively registered holder to move the latch outwardly 5 and so release the bolt. Member 41 is hereinafter known as the coin controlled member, or coin controlled latch releasing member. Other parts about to be described associated therewith are known, together with 10 the said member, as the coin controlled means.

The article holders are each riveted as at 42, to a face plate 43. Said plate is in turn carried by a sleeve 44 which turns on the 15 axle. The sleeve, plate, and assembly of article holders are collectively known as the magazine; the individual article holders serving to provide a revolvable magazine having a plurality of pockets, each fitted 20 with a hinged closure. The magazine may be constructed as a single piece in which the pockets are provided as required. The end walls of the holders, which are opposed to the walls which carry the latches, are each 25 provided with an opening 45, thru which the contents of the holder may be seen. When required for loose or irregular shaped articles, said openings may each be fitted with a translucent sheet (not shown) of 30 glass, celluloid or the like. A rear extension to the chute extends upwardly as at 48, so that the latch of the adjacent closure can not be reached thru the chute.

The article holders, in the embodiment illustrated, are each designated respectively by numerals, in this case, 1 to 30 inclusive. In front of the outer end of the axle, just 35 behind the glass, there is provided a menu card holder 46, having a depending arrow shaped end pointing downwardly to the chute. When the nature of the articles or packages being vended is such that their 40 contents cannot be determined by looking thru the openings in the article holders, the menu-card may be consulted. The menu-card designates the article wanted by a numeral. The magazine is then turned until that numeral is just below the point of 45 the arrow. When so positioned the article holder, containing the designated article, is in operative registration with the chute and the latch releasing member.

To selectively position the article holders there is provided a handle 49, externally of 50 the casing which is connected to a shaft 50, said shaft extends into the interior of the casing and carries a small pulley 51. The sleeve of the magazine is provided with a 55 larger pulley 52, fixed thereto. A belt 53 connects the respective pulleys so that turning of the exterior selecting handle will 60 slowly turn the magazine.

It is to be understood that the magazine 65 is freely revolvable regardless of whether or not a coin is placed in the machine and

it is even possible to rotate the magazine in either direction so that the selected article may be brought into registration with the chute by the shortest route. Suitable means, not shown, may be provided for imposing 70 slight resistance to the magazine so that when the magazine and contents is unbalanced it will tend to remain wherever it is set by the selecting handle. The handle preferably is arranged to drive the magazine 75 thru the friction belt shown so that when the latch releasing means is in operation accidental turning of the selecting handle may cause the belt to slip without turning the handle. For reasons apparent hereinafter, 80 the magazine is held locked while the latch releasing member is in other than normal inoperative position.

Any suitable coin controlled means may be employed for moving the latch releasing 85 member, but in the embodiment shown we provide a particular means which we will now describe. Said means includes a horizontal, oscillatable shaft 55, extending forwardly thru the casing and terminating in 90 an operating lever externally of the casing. Said lever extends thru the frame and is fitted at the rear end with a coin engaging oscillatable segment 57. Said segment is provided with a step 58, terminating in a 95 horizontally disposed foot 59. Normally the segment 57 is free to be oscillated without interference, but produces no result unless a coin, such as 60, rests on the foot.

The coin controlled means further includes another oscillatable segment in juxtaposition to the first named segment. Said segment is provided with an integral sleeve 61, which fits loosely around the shaft 55. A bearing 62 is carried by the frame, in 100 which bearing the sleeve 61 is freely oscillatable. Thus the bearing supports the sleeve 61, and said sleeve in turn acts as a bearing for the shaft. There is provided an L shaped arm 62, which is shown here as 105 being integral with the sleeve. Said arm terminates in the vertically disposed, vertically movable latch releasing member.

The machine includes a suitable coin chute 110 63, here shown as being a simple enclosed chute. Said chute may have any of the usual slug eliminators and the like, incorporated therein, but inasmuch as devices of that character form the subject of a co-pending application, such device is not shown 115 herein. The chute enters the casing as at 65, leading from a coin slot 66 downwardly over the inner end of the shaft and terminates in a coin ejecting end 67. Said end is aligned with a coin holding slot 67^a provided 120 in the segment. When a coin drops out of the chute it enters slot 67^a, in the segment, and is brought to a stop by the foot on the other segment. Thus the coin forms a 125 physical medium between the two segments. 130

As the operating lever is moved, the shaft is moved to rock the stepped segment. The coin causes the stepped segment to impel the other segment to move the integral sleeve 5 and the latch releasing member. As soon as the stepped segment is allowed to return the foot moves out from under the coin slot and the coin is released and falls thru said slot to a coin box, (not shown).

10 The magazine is provided with a star wheel 70, having a plurality of V notches, corresponding in number to the article holders. To the arm 62, as at 71, there is pivoted a vertically extended link 72. Below the 15 star wheel a centering pawl 73 is provided which is pivoted to the frame as at 74. Said pawl has a pointed end 75 adapted to enter any V notch which is approximately aligned with it. The pawl rests on a cam 76 which 20 is pivoted to the frame as at 77. The upper end of the link as at 78 is pivoted to an extension 79 of the cam. Thus upward movement of the arm 62 raises the extension end of the cam and rocks the pointed end of the 25 pawl upwardly so that it enters the V notch with which it is approximately aligned. The parts just described are so arranged that the first upward movement of the arm 62 will operate the cam to in turn operate the 30 pawl. Thus, first movement of the arm 62, causes the star wheel to turn slightly and to become locked in such position until the arm 62 is returned to almost normal position. After the pawl is moved into a V notch, the 35 cam is free to turn because of the coaxial perimeter 79^a thereof, which only holds the pawl in place without tending to move it further.

40 The star wheel and its notches are so arranged that when the pawl is in place a latch will be in operative registration with the latch releasing member. Movement and locking of the star wheel is of course timed to take place before the latch release comes 45 in contact with a registered holder.

46 From the foregoing description of the parts, and from the foregoing descriptions of the actions of some of the parts, the operation of the machine is quite apparent but 50 the following will serve to more fully explain the operation of the machine as a whole. A prospective patron, facing the machine, can quickly learn the entire contents of the machine by looking at the exposed ends of the article holders, or by reference to the menu-card. If an article holder is empty the patron can see it to be a fact. A further protection for the patron is that 55 he can see any article holder which is in registration with the arrow and discharge chute. There is no excuse for selecting an empty article holder. The machine may include means for returning a deposited coin, in case the patron operates the machine with 60 an empty holder in position, but such means

is set forth in my co-pending application Serial Number 56,707, and needs no description herein.

65 Inspection and selection may be carried on by any prospective buyer without need of 70 depositing a coin. When an article is selected a coin may be dropped in the chute and allowed to gravitate to the coin controlled parts. Depression of the operating lever will then cause the latch releasing 75 member to move upwardly as explained. If the article holder has not been positioned correctly, the pawl will act on the star wheel to properly position the holder just before the latch release comes into contact with the 80 latch. The registered latch is downwardly directed as shown and as the latch releasing member moves up against its inclined surface, the latch moves outward to release the bolt. The spring which connects the bolt 85 with the yoke, shortens in effective length and draws the upper end of the latch downwardly. As a result the lower end of the bolt moves downwardly and moves the closures into open position. Any loose pack- 90 ages or articles contained in the holder would ordinarily escape by gravity and fall thru the open closures into the chute. In the case of a boxed sandwich, or the like, the box should fit quite closely in the article 95 holder; it is understood that a sandwich, or the like, should be first wrapped in suitable paper before being inserted in the box. The paper acts to protect and cushion the sandwich, and the sandwich so wrapped should 100 be a close fit in the box. To prevent jarring of the sandwich, the box in turn should be a close fit in the holder. Such practice is common, but is here mentioned to show that under some conditions a boxed sandwich 105 might not, and in fact should not, be able to escape by gravity. The spring pressed movable wall, however, will positively eject the boxed sandwich without injury.

110 So long as the latch release is in operative position, or in other than inoperative position, the pawl engages the star wheel and if the selecting handle is turned the belt will slip without moving the magazine. Obviously, movement of the magazine with the 115 latch release in operative position would either act to jam, disturb or break some parts, or result in successive packages being ejected. Until the coin controlled parts are allowed to return to normal position, the 120 magazine cannot be moved, and before the parts are returned, the contained coin is released.

125 The modified form of the invention has the discharge chute located uppermost of the casing. In such embodiment the other parts are suitably arranged to conform to the location of the discharge chute. Since the article holders are capable of ejecting their contents, an article holder which is 130

opened to the chute shown will move its articles up until it projects from the chute sufficiently to be reached by the purchaser.

It will be apparent now that we have provided what might well be called a mechanical coin controlled store adapted to mechanically vend almost anything from a paper of pins to a piece of pie, the number of different articles being limited only by the number of article holders; and it will also be apparent that we have provided a fully selective machine in which a very satisfactory percentage of the volume of the machine may be occupied by goods to be vended, and

While we have shown and described a specific embodiment of our invention, and a specific form of article holder, and specific arrangement of article holders, and while we specify specific constructions and arrangements of parts, we have been specific only that we might describe one practical embodiment of our invention, and we do not limit ourselves to any specific construction or arrangement of parts, and we may alter the construction and arrangement of parts and employ other suitable types of article holders without enlarging the scope of our invention and without departing from the spirit thereof, within the appended claims.

We claim:

1. In a selective vending machine, a casing enclosing a space, a discharge chute leading from said space outwardly, a plurality of article holders collectively movable within said space whereby any article holder may be operatively registered with said chute, each article holder having an open end which is in discharging communication with said chute, when the holder is aligned with said chute, means for each article holder tending to eject the contents thereof, locking means normally acting to prevent such ejection, and a member movable to release the locking means of any article holder which is in operative registration with the chute, and means operable externally of the casing to move the article holders collectively to dispose any selected article holder in registration with the chute.

2. In a selective vending machine, a casing enclosing a space, a discharge chute leading from said space outwardly, a plurality of article holders collectively movable within said space whereby any article holder may be operatively registered with said chute, each article holder having an open end which is in discharging communication with said chute when the holder is aligned with said chute, a spring for each article holder tending to thrust the contents of the holder thru the open end, a closure for the open end movable to closed position to retain the contents against the thrust of the spring, a latch inaccessible thru said

chute holding said closure in closed position, a member operable to move the latch to release the closure of an article holder which is operatively registered with the chute, and selecting means operable externally of the casing to move any selected one of the article holders into operative registration with said chute, said closure when in closed position rendering the spring normally ineffective, and selecting means operable extraneously of the casing to move any selected article holder into registration with the chute.

3. In a selective vending machine, a casing enclosing a space, a discharge chute leading outwardly from said space, a plurality of article holders, collectively movable in said space whereby any selected article holder may be moved into operative registration with the chute, each article holder having an open end which is in discharging communication with the chute when the corresponding holder is registered with the chute, means carried by each article holder tending to eject the contents thereof, a hinged closure for the open end of each article holder, a latch acting to hold the closure in closed position to normally prevent ejection of the contents of the corresponding article holder, means operable externally of the casing to collectively move the article holders to dispose a selected article holder in registration with the open end of the chute, a member located adjacent the chute movable into contact with the latch of an article holder which is registered with the chute to effect release of the corresponding closure, and means acting to prevent movement of the holders when said member is in other than normal inoperative position.

4. In a selective vending machine, a movable magazine embodying a plurality of article holders, a casing enclosing the magazine, a single fixed discharge chute, means operable externally of the casing to revolve said magazine to dispose any selected one of the holders in registration with said chute, each holder having an open end arranged to be directed toward said chute when the holder is registered therewith; said chute being so disposed that an article may gravitate into the chute from a registered holder when free to do so, a closure for each article holder normally preventing the contents of the holder from gravitating to the chute, said closure being the sole means of retaining the contents of a holder; whereby opening of the closure will release the contents, and a member located adjacent the chute and operable to open the closure of an article holder which is registered therewith, and means acting to prevent movement of the magazine when the member is in other than inoperative position.

5. In a selective vending machine a cas-

ing provided with a discharge chute, a plurality of article holders collectively movable and disposed in the casing above the chute and each having an open end downwardly directed whereby the contents of an article holder may gravitate therefrom into the chute when free to do so, a closure for each article holder movable to closed position to retain the contents of a holder and movable to open position to release the contents thereof, a selecting mechanism operable from externally of the casing to collectively move the article holders to dispose any selected one of all the article holders in registration with the chute, a latch holding said closure in closed position and being movable to release the closure, a member disposed adjacent to the chute, movable to move the latch to release the closure of the article holder which is then in registration with the chute, and means to prevent movement of the article holders.

6. In a selective vending machine a casing provided with a discharge chute, a plurality of article holders collectively movable and disposed in the casing above the chute and each having an open end downwardly directed whereby the contents of an article holder may gravitate therefrom into the chute when free to do so, a closure for each article holder movable to open position to release the contents thereof, a selecting mechanism operable from externally of the casing to collectively move the article holders to dispose any selected one of all the article holders in registration with the chute, a member operable to move the closure of an article holder which is in registration with the chute to open position, releasable means on each article holder operable to open the closure, said member operable to release the means on that closure which is then in registration with the chute, and means operative co-incident with the said member to prevent movement of the article holders.

7. In a selective vending machine, a hollow drum-like casing having vertical front and back walls respectively and a peripheral wall; said front wall embodying a circular window, a horizontal fixed axle projecting rigidly from adjacent the back wall, a magazine revolvably supported by said axle, a plurality of radially arranged article holders to said magazine, a vertical discharge chute extended through the peripheral wall of said casing, so disposed that any selected one of the article holders may be moved, by rotation of the magazine, into discharging registration with regard to said chute; each article holder having an open end arranged to register therewith, a handle externally of the casing, connections between said magazine and handle whereby the handle may be moved to rotate the magazine to dispose any selected article holder in registration with said opening, means whereby the contents of an article holder is determined, means to indicate to the operator, which holder is in registration with said opening, means normally retaining the contents of an article holder; said casing walls co-acting to render said retaining means inaccessible thru the opening, and a single member operative to release the contents of an article holder then in registration with said opening.

8. In a selective vending machine, a plurality of juxtaposed boxlike article holders each having an open end thru which contents may be inserted and removed, closures, one for each holder, movable to closed position to retain the contents of the corresponding holder, a spring for each closure tending to move the corresponding closure to open position, retractile bolts one for each holder, connected to move with the corresponding closure, latches, one for each holder adapted to engage the corresponding bolt to hold the corresponding closure in closed position; a casing having walls providing a space closed to unauthorized access, all latches being disposed in said space, and a member operable to move a selected latch out of engagement with the corresponding bolt.

9. In a selective vending machine, a plurality of juxtaposed boxlike article holders each having an open end thru which contents may be inserted and removed, closures, one for each holder, movable to closed position to retain the contents of the corresponding holder, a spring for each closure tending to move the corresponding closure to open position, retractile bolts one for each holder, connected to move with the corresponding closure, latches, one for each holder adapted to engage the corresponding bolt to hold the corresponding closure in closed position; a casing having walls providing a space closed to unauthorized access, all latches being disposed in said space, a latch moving member operative to move the latch to release the closure of any one of the article holders which is then in operative registration with said member, said article holders collectively movable to dispose any selected one of the holders in operative registration with the latch raising member.

10. In a selective vending machine, a plurality of juxtaposed boxlike article holders each having an open end thru which contents may be inserted and removed, closures, one for each holder, movable to closed position to retain the contents of the corresponding holder, a spring for each closure tending to move the corresponding closure to open position, retractile bolts, one for each holder, connected to move with the corresponding closure, latches, one for each holder adapted to engage the corresponding bolt

- to hold the corresponding closure in closed position; a casing having walls providing a space closed to unauthorized access; all latches being disposed in said space, a latch 5 moving member operative to remove the latch to release the closure of any one of the article holders which is then in operative registration with said member, said article holders collectively movable to dispose any 10 selected one of the holders in operative registration with the latch raising member, locking means operable coincident with said latch moving member, to prevent movement of the article holders while said member is 15 in other than inoperative position.
11. In a selective vending machine a casing provided with a discharge opening, a member movable thru a fixed path adjacent said opening, a revoluble magazine, a plurality of radially arranged outwardly opening article holders carried collectively by said magazine, closures, one for and carried by each article holder, a latch carried by each article holder to hold the corresponding 20 closure in closed position; the latches being each independently releasable to allow the corresponding closure to be opened; said magazine movable to dispose any article 25 holder with its outer end in registration with said opening while the latch of the corresponding holder is disposed in the path of the movable latch releasing member. 30
12. In a selective vending machine a casing provided with a discharge opening, a member movable thru a fixed path adjacent said opening, a revoluble magazine, a plurality of radially arranged outwardly opening article holders carried collectively by said magazine, closures, one for and carried by each article holder, a latch carried by each article holder to hold the corresponding closure in closed position; the latches being each independently releasable to allow the corresponding closure to be opened; said magazine movable to dispose any article 35 holder with its outer end in registration with said opening while the latch of the corresponding holder is disposed in the path of the movable latch releasing member and means for locking the magazine against 40 movement while the latch release is in other than normal non-latch-releasing position. 45
13. In a selective vending machine a casing provided with a discharge opening, a member movable thru a fixed path adjacent said opening, a revoluble magazine, a plurality of radially arranged outwardly opening article holders carried collectively by said magazine, closures, one for and carried by each article holder, a latch carried by each article holder to hold the corresponding closure in closed position; the latches being each independently releasable to allow the corresponding closure to be opened; said magazine movable to dispose any article 50 holder with its outer end in registration with said opening while the latch of the corresponding holder is disposed in the path of the movable latch releasing member. 50
